Inventor
John P. Vaughn.
Brace Attorney

UNITED STATES PATENT OFFICE.

JOHN PRESTON VAUGHN, OF ST. PETERSBURG, FLORIDA.

PROTECTOR FOR DISTRIBUTOR WIRES.

Application filed September 23, 1924. Serial No. 739,329.

To all whom it may concern:

Be it known that I, JOHN PRESTON VAUGHN, a citizen of the United States, residing at St. Petersburg, in the county of Pinellas, State of Florida, have invented certain new and useful Improvements in Protectors for Distributor Wires; and I do hereby declare the following to be a full, clear, and exact description of the invention, such as will enable others skilled in the art to which it appertains to make and use the same.

This invention relates to new and useful improvements in protecting devices, and particularly to devices for protecting the ignition circuits of automobile engines against shortcircuiting.

The principal object of the invention is to provide a device which will cover the distributor of an internal combustion engine ignition circuit so as to prevent entrance of water, oil, or other means which would short circuit the ignition circuit.

Another object is to provide a device of this character which is readily adjustable to different types and sizes of distributors, and which is constructed to deflect water, which would strike the upper end of the device, to a safe distance away from the distributor.

Another object is to provide a cover of this character which permits free circulation of air therebeneath, by means of external bosses described hereinafter, whereby to prevent heating and condensation within the cover.

Other objects and advantages will be apparent from the following description when taken in connection with the accompanying drawing.

In the drawing:

Figure 1 is an elevation of the device shown as applied to a distributor.

Figure 2 is an enlarged vertical longitudinal sectional view through the device, the wires being in elevation.

Referring particularly to the accompanying drawing, 10 represents a portion of the distributor of an automobile engine, and 11 the heavily insulated conductor wires leading to the various spark plugs, and in connection with which the present invention is particularly adapted for use.

The protector comprises an elongated molded rubber sheath 12, one end of which is open, as indicated at 13, to permit the sheath being slipped onto the end of the

distributor 10. The other end of the sheath is formed with a dome-shaped portion 14, and where this portion joins the body of the sheath, there is formed a rib or flange 15, for the purpose of directing water or oil, which might fall onto the dome 14, outwardly away from the sheath. Formed in the center of the crown of the dome 14 is an opening 16, and in the sides of the dome, 60 surrounding this central opening, and in proper spaced relation thereto, and to each other are the additional openings 17. Formed on the outer convex face of the dome around each opening, and projecting 70 from the dome, is a nipple 18, and disposed through each of these nipples is a conductor wire 11, said conductor being secured to its appropriate binding screw within the distributor. The outer ends of the wires connect with the spark plugs of the engine, and the source of current, respectively, not shown, but as will be readily understood.

Formed in diametrically opposite parts of the lower end of the skirt of the body is 80 a longitudinally extending boss resulting in the interiorly arranged elongated sockets thereabove, each of said sockets being arranged to receive and loosely engage the retaining clip of the distributor head. 85

It will be noted that the lower end of the skirt of the body does not tightly fit the distributor cap, nor do the bosses tightly fit the clip holding on the distributor head, with the result that there is provided sufficient space between the cover and distributor cap to permit passage of air. This passage of air beneath the cover prevents heating within the cover and subsequent condensation, whereby collection of moisture on 90 the wires and terminals is effectively obviated.

The provision of the recesses or bosses serve to prevent stretching of the rubber skirt when applying or removing the cover, 100 whereby to prolong the life of the cover.

From the foregoing it will readily be seen that I have provided a cover for an ignition distributor which prevents entrance of external moisture to the wires and terminals, 105 and also provides for breathing of the distributor, whereby to prevent condensation and accumulation of moisture beneath the cover.

As clearly seen in the sectional view, Fig. 110 2, the nipples are of such size that the conductors fit tightly therein, thus effectively

excluding moisture of any kind from the interior of the protector, and thereby preventing access of such moisture to the metallic connections within the distributor, 5 and the short circuiting of the ignition circuit.

The body of the sheath, and the nipples, are molded in one piece, it being the practice to make the skirt of the sheath, or that 10 portion surrounding the open end, of greater length than necessary for ordinary purposes so that it may be cut off if too long, while being of approximately the right length for a distributor of greater length 15 than the ordinary distributor.

The sheath or protector is treated by any well known process to render it oil resisting, as well as waterproof and moistureproof; and the entire device is of substantial thickness 20 throughout, that is, of the same or greater insulation strength as the insulation of the wires leading from the distributor to the plug.

While the drawing illustrates the nipple 25 carrying end of the sheath as dome-shaped, I wish it understood that this portion may be oval, square, oblong, or any other outline desired.

Attention is called to the fact that should 30 the wires become loosened from their permanent fastenings within the distributor, the nipples will effectively hold the wires from being detached from such fastenings.

It will be noted that the nipples on top 35 of device are in true alignment with the sockets on distributor cap, so that once the

device is installed the wires are in proper firing order, thus permitting the layman, or mechanic, to remove device and wires from the distributor cap for any purpose whatsoever and to be able to replace wires in their exact position, as the side bosses over the spring clips act as a natural guide in replacement of the wires.

40

What is claimed is:

45

1. A protector for electric distributors, timers, and the like, comprising a molded flexible resilient sheath having one end open to receive the distributor or timer, and the other end closed, said closed end being provided with a plurality of outwardly projecting flexible resilient electric conduit receiving nipples.

50

2. A protector comprising a molded live rubber sheath having a skirt on one end and the other end formed with an outwardly projecting closing wall, said wall being formed with a plurality of openings and outwardly projecting flexible resilient nipples surrounding said openings, said skirt having internal recesses forming breathing 55 passages.

60

3. A protector comprising a molded flexible resilient sheath having a skirt on one end and the other end formed with a wall having a plurality of flexible resilient nipples, said skirt having external longitudinal bosses providing internal recesses which latter form breathing passages.

65

In testimony whereof, I affix my signature.

JOHN PRESTON VAUGHN.
